UNITED STATES PATENT OFFICE

172,030

FLEXIBLE TUBE DISPENSING DEVICE

J. Clifford Johnson, Port Washington, N. Y.

Application April 21, 1953, Serial No. 24,611

Term of patent 14 years

(Cl. D4—3)

To all whom it may concern:

Be it known that I, J. Clifford Johnson, have invented a new, original, and ornamental Design for Flexible Tube Dispensing Device, of which the following is a specification, reference being had to the accompanying drawing, forming a part hereof.

Fig. 1 is a side view of a flexible tube dispensing device embodying my new design.

Fig. 2 is a plan view thereof.

Fig. 3 is an end view looking in the direction of the slotted end of the device; and

Fig. 4 is an end view looking in the direction of the fingerpiece end of the device.

I claim:

The ornamental design for a flexible tube dispensing device, as shown.
